PAPER MACHINE HEAD BOX

Jerome J. Luebke, West De Pere, Wis., assignor,
by mesne assignments, to Marathon Corpora-
tion, Menasha, Wis., a corporation of Wisconsin

Application May 12, 1951, Serial No. 225,959

13 Claims. (Cl. 92—44)

1

The present invention relates to paper making machines of the Fourdrinier type, and more particularly to head boxes or flow boxes for such machines.

An object of the invention is to provide an improved head box of simple, durable and inexpensive construction in which the pulp or stock will be uniformly distributed or spread over the width of the head box and caused to flow from the head box in a smooth flat stream onto the paper-forming surface of the Fourdrinier wire belt.

Another object is to provide a flow-distributing head box in which the incoming stock flows transversely thereof, and which is so arranged as to conserve floor space.

A further object is to provide simple but effective means for adjusting or equalizing the distribution of the stock over the width of the head box.

The invention further consists in the several features hereinafter described and claimed.

In the accompanying drawings,

Fig. 1 is a longitudinal sectional elevational view of a head box constructed in accordance with the invention;

Fig. 2 is a top view of the stock-distributing portion of the head box, parts being broken away and parts being shown in section;

Fig. 3 is a sectional elevational view taken generally on the line 3—3 of Fig. 2;

Fig. 4 is a sectional elevational view taken generally on the line 4—4 of Fig. 2, and

Fig. 5 is a fragmentary sectional detail view taken generally on the line 5—5 of Fig. 3.

In these drawings, 10 designates generally a head box or flow box of the invention, and 11 designates a breast roll over which is trained a conventional Fourdrinier wire belt 12 presenting a paper-forming surface. The head box is provided at its front end with a discharge nozzle or channel 13 of rectangular slot-like cross-section extending over the width of the head box and terminating at an orifice-forming slice 14 from which the pulp or stock spouts under the pressure of a gravity head in a smooth flat stream or sheet onto the traveling wire belt. The discharge nozzle, which is of metal construction, is here shown to be forwardly and downwardly inclined and has a portion with sloping parallel top and bottom walls between which is placed a flow evener 15 of grid-like or honeycomb cross-section. The slice includes upper and lower walls or lips which converge forwardly to form the discharge orifice, the swingably mounted upper lip being operatively connected to a suitable adjust-

2

ing mechanism 16 for varying the width of the orifice. The downstream end of the lower slice lip is horizontal and close to the upper run of the wire belt, this slice lip end being disposed a short distance rearwardly of the vertical center line of the breast roll. The head box and slice are mounted on a suitable framework 17.

The head box, which is of generally rectangular shape and may be largely of reinforced wood construction, includes parallel vertical side walls 18 and 19, an upper vertical front wall 20, a lower vertical front wall 21 offset rearwardly from the upper front wall, an upper vertical rear wall 22, a lower vertical rear wall 23 offset forwardly from the upper rear wall, a horizontal bottom wall 24 which extends to the side walls and to the lower front and rear walls, and a horizontal shelf or platform 25 which extends from the lower edge of the upper rear wall to the upper edge of the lower rear wall. The inclined discharge nozzle or channel 13 extends from the space between the upper and lower front walls.

The head box has formed therein various passages and chambers hereinafter described to distribute or spread the incoming stock, to reduce turbulence, and to provide for a smooth gravity flow of well-mixed stock into the discharge nozzle 13.

An inlet or distributing chamber 26 of elongated rectangular shape is formed between the upper rear head box wall 22 and the upper portion of a transversely extending vertical baffle wall or dam 27, the shelf or platform 25 forming the bottom of this chamber. The baffle wall 27 is spaced forwardly from the lower rear wall 23 and forms therewith a vertical down-pass 28 extending over the width of the head box and communicating at its upper end with the elongated distributing chamber, which also extends over the width of the head box. The baffle wall 27 is here shown to be of double construction and to have its ends mortised into the side walls of the head box. The baffle wall 27 and upper end wall 22 are connected at their upper edges by cross bars 29. The horizontally extending distributing chamber has a lateral extension 30, Figs. 2 and 4, formed between a projecting portion of the upper rear wall 22 and a parallel vertical wall 31 spaced forwardly from the upper rear wall and disposed in the plane of the lower rear wall 23. The wall 31 is connected to the side wall 19 of the head box at a junction presenting a rounded inner surface 32, and the outer end of the extension is closed by a vertical wall 33 which is parallel to the side wall. A curved metal elbow 34, supported on standards 35 and

36, has a rearwardly projecting horizontal intake 37 with a flanged end connected to a horizontal stock pipe 38, Fig. 1, and has an upwardly projecting delivery end portion 39 secured in the bottom of the lateral extension 38 of the distributing chamber 26, the elbow being of rectangular cross-section except for the intake portion 37 thereof which converges to a circular end to match the stock pipe 38. The upper portion of the elbow 34 has parallel, vertical front and rear walls 40 and 41, Fig. 1, and upwardly diverging side walls 42 and 43, Fig. 4, the latter wall having at its upper end a horizontal lip 44 resting on the end of the platform 25. The vertical wall 40 is aligned with the inner vertical 15 surface of the laterally extended upper rear wall 22 of the head box. Arcuate turning vanes 45 are mounted in the curved portion of the elbow, and are spaced from each other and from the cylindrically curved walls of the elbow to form 20 flow passages of approximately equal cross-sectional area.

also serves to facilitate release of air bubbles from the stock.

Between the baffle wall 13 and the upper front wall 20 is formed a chamber 18 to which stock is delivered from the up-pass 16. A suitable head of stock is maintained in this chamber from which stock flows by gravity into the discharge nozzle 13. The height of the stock in the chamber 18 determines the spouting velocity of the stock at the slice 14, this velocity corresponding to the linear speed of the Fourdrinier wire belt. The stock level in the chamber 18 is adjusted by varying the rate of stock inflow to the distributing chamber. The narrow passage 14 between the lower ends of the down-pass 15 and the up-pass 16 increases the stock velocity at this region, so as to effect mixing of the stock shortly before it is discharged from the head box. If it is observed that the velocity is too great, resulting in excessive disturbance of the stock when it enters the discharge nozzle 13, the baffle wall or dam 13 is raised a sufficient amount to reduce or eliminate the disturbance.

In the operation of the paper machine, pulp or stock is pumped at a selected rate of flow through the stock pipe 38 and passes upwardly in the elbow 34 into the lateral extension 30 of the distributing chamber 26, the stock flow being distributed over the cross-section of the rectangular delivery end 39 of the elbow by the turning vanes 45. The velocity of the stock decreases as the stock passes through the elbow. From the chamber extension 30 the stock first flows horizontally along the elongated distributing chamber crosswise of the head box and is then turned or directed forwardly of the head box by the curved passage-forming vanes 46 to 51, so that the stock flow in the down-pass 28 of the head box is divided or distributed across the width of the head box. The optimum distribution can readily be provided by laterally shifting the upstream ends of the vanes 46 to 51 by the adjusting rods 57. These vanes serve not only to distribute and direct the flow but also to reduce turbulence of the stock before it enters the down-pass 28. The downstream vane projections 55 act to straighten the flow in the down-pass. The flow in the down-pass is produced by the head of stock in the distributing chamber rather than by direct pumping pressure, and is unaffected by pump pulsations. From the lower end of the down-pass the stock flows through the curved passage 66 into the bottom of the stilling chamber 67, and thence upwardly and over the inclined dam-forming table 70 through the down-pass 15, the bottom passage 74, the up-pass 16, and into the discharge chamber 18. Mixing of the stock is effected as the stock flows at increased velocity through the narrow passage 14. The stock then flows into the discharge nozzle 13 under the head of stock in the chamber 18, passes through the flow evener 15 and the slice 14, and spouts from the slice orifice to lay a smooth flat stream of stock of glassy appearance onto the traveling wire belt. The stock entering the discharge nozzle is free from major disturbances, and any remaining minor disturbances are removed in the flow evener 15, the extended wall surfaces of which exert a mild mixing action on the stock. The smooth flat stream of well-mixed stock laid on the wire belt results in the formation of a paper sheet which is of uniform thickness and good quality.

The stock distributing means at the inlet or

entrance portion of the head box is of such character that it will permit inexpensive construction and conserve floor space, while affording an even distribution or spreading of the stock over the width of the head box.

What I claim is:

1. In a paper making machine, a head box having at its rear portion a stock distributing chamber extending transversely of the head box and provided with a stock intake at an end portion of said chamber adjacent to a side of the head box, said chamber having an outlet extending along the front thereof and substantially across the width of the head box, and vertical flow-directing wall members in said chamber curved through substantially 90° and forming flow-dividing passages between said intake and said outlet, said curved wall members having upstream ends projecting toward said intake in a direction transversely of the head box and having downstream ends projecting forwardly in the head box and spaced across the width of the head box to distribute the flow of stock through said outlet.
2. In a paper making machine, a head box having a stock distributing chamber extending transversely thereof and provided with a stock intake at an end portion of said chamber, a down-pass in said head box extending substantially across the width of said head box, said down-pass having an entrance at its upper end communicating with the bottom of said chamber along the front of said chamber, and vertical flow-directing wall members in said chamber forming flow-dividing passages between said intake and said down-pass, said wall members being curved through substantially 90° and having upstream ends projecting toward said intake transversely of the head box and having downstream ends projecting forwardly in the head box and spaced across the width of the head box to distribute the flow of stock into said down-pass.
3. In a paper making machine, a head box having a stock distributing chamber extending transversely thereof and provided with a stock intake at an end portion of said chamber, a down-pass in said head box extending substantially across the width of said head box, said down-pass having an entrance at its upper end communicating with the bottom of said chamber along the front of said chamber, and vertical flow-directing wall members in said chamber curved through substantially 90° and forming flow-dividing passages between said intake and said down-pass, said curved wall members having upstream ends projecting toward said intake and having downstream ends projecting forwardly in the head box and spaced across the width of the head box to distribute the flow of stock into said down-pass, the downstream ends of said wall members extending over the entrance of said down-pass.
4. In a paper making machine, a head box having a stock distributing chamber extending transversely thereof and provided with a stock intake at an end portion of said chamber, a down-pass in said head box extending substantially across the width of said head box, said down-pass having an entrance at its upper end communicating with the bottom of said chamber along the front of said chamber, and vertical flow-directing wall members in said chamber curved through substantially 90° and forming flow-dividing passages between said intake and

said down-pass, said wall members having upstream ends projecting toward said intake transversely of the head box and having downstream ends projecting forwardly in the head box and spaced across the width of the head box to distribute the flow of stock into said down-pass, the downstream ends of said wall members extending over the entrance of said down-pass and having portions projecting downwardly into said down-pass.

5. In a paper making machine, a head box having a stock distributing chamber extending transversely thereof and provided with a stock intake at an end portion of said chamber, said chamber having an outlet extending along the front thereof and substantially across the width of the head box, and vertical turning vanes in said chamber forming flow-dividing passages between said intake and said outlet, said vanes being curved through substantially 90° and having upstream ends projecting toward said intake and having downstream ends projecting forwardly in the head box and spaced across the width of the head box to distribute the flow of stock through said outlet, the upstream portions of said vanes being spaced to form entrances for said passages, and the upstream ends of at least some of said vanes being laterally displaceable to vary the width of said entrances for adjustably dividing the stock flow through said passages, and means for retaining said upstream vane ends in laterally adjusted position.

6. In a paper making machine, a head box having a stock distributing chamber extending transversely thereof and provided with a stock intake at an end portion of said chamber and with a bottom wall, said chamber having an outlet extending along the front thereof and substantially across the width of the head box, and vertical turning vanes in said chamber upstanding from said bottom wall, said vanes being curved through substantially 90° and extending between said intake and said outlet and forming flow-dividing passages, said vanes having downstream ends projecting forwardly in the head box and spaced across the width of the head box to distribute the flow of stock through said outlet, the upstream ends of said vanes being disposed in echelon relation.

7. In a paper making machine, a head box having a flow spreading inlet chamber with a stock intake and with an outlet in the head box extending substantially across the width of the head box, flow-directing wall members in said chamber forming flow-dividing passages between said intake and outlet, said wall members being curved through substantially 90°, the downstream ends of said wall members being spaced across the width of the head box adjacent to said outlet, said passages having upstream entrances, and the upstream ends of at least some of said wall members being laterally displaceable to vary the width of said entrances for adjustably dividing the stock flow through said passages, and means for retaining said displaceable wall member ends in laterally adjusted position.

8. In a paper making machine, a head box having a rear portion with a horizontally disposed stock distributing chamber extending transversely of the head box and provided with a bottom wall and with a stock intake at an end portion of said chamber, the horizontal dimension of said chamber in a direction lengthwise

of the head box being substantially smaller than the width of said head box, said chamber having an outlet along its front portion extending substantially across the width of the head box and communicating with a second chamber of the head box, and vertical flow-directing wall members in said distributing chamber upstanding from said bottom wall and forming elbow-shaped flow-dividing passages, said wall members being curved through substantially 90° and having downstream end portions extending forwardly in the head box and spaced across the width of the head box to distribute the flow of stock through said outlet and said wall members having upstream ends substantially at right angles to the downstream ends and projecting toward said stock intake.

9. In a paper making machine, a head box having a front portion with a stock discharge opening and having a rear portion with a transversely extending stock distributing chamber, said chamber having a bottom wall higher than said discharge opening and further having a stock intake at an end portion of said chamber, a down-pass extending substantially across the width of the head box and having a slot-like entrance at its upper end extending along the front of said bottom wall and communicating with said chamber, and flow-directing wall members in said chamber upstanding from said bottom wall, said wall members being curved through substantially 90° and forming flow-dividing passages which extend between said intake and said down-pass and widen in downstream direction, said wall members having upstream ends projecting transversely of the head box toward said intake and having downstream ends projecting forwardly in the head box and spaced across the width of the head box to distribute the flow of stock into said down-pass.

10. In a paper making machine, a head box having a stock distributing section with a stock intake and a stock outlet, and vertical flow-directing wall members in said section curved through substantially 90° and forming flow spreading passages between the intake and the outlet, said passages having upstream entrances, the upstream ends of at least some of said wall members being laterally displaceable to vary the entrance width of the associated passages for adjustably dividing the stock flow through said passages, and deflecting and retaining means for the displaceable upstream ends of said wall members having actuating portions at the exterior of said head box.

11. In a paper making machine, a head box having a stock distributing section with a stock intake and a stock outlet, and vertical flow-directing wall members in said section forming flow spreading passages between the intake and the outlet, said wall members being curved through substantially 90°, the upstream portions of said wall members forming entrances for the passages, the upstream ends of at least some of said wall members being laterally displaceable to vary the entrance width of the associated passages for adjustably dividing the stock flow through said passages, and axially shiftable retaining rods extending transversely of and operatively connected to the displaceable upstream ends of said wall members for holding said last-named ends in laterally adjusted position.

12. In a paper making machine, a head box having a front portion with a stock discharge opening and having a rear portion with a trans-

versely extending stock distributing chamber, said head box having substantially parallel side walls one of which forms an end of said chamber, the other end of said chamber extending beyond the other of said side walls and having a bottom stock intake, said chamber having a bottom wall higher than said stock discharge opening, a down-pass in said head box extending substantially across the width of said head box and having a slot-like entrance at its upper end extending along said chamber bottom wall and communicating with said chamber, and flow-directing means in said chamber forming with said bottom wall a plurality of flow-dividing passages extending between said intake and the entrance of said down-pass for distributing the flow of stock into said down-pass, said flow-directing means including vertical vanes curved through substantially 90°.

13. In a paper making machine, a head box having a horizontally disposed stock distributing chamber extending transversely thereof and provided with a bottom wall, said chamber having an end portion projecting laterally from a side of the head box and provided with a stock in-

take from which stock flows horizontally along said chamber crosswise of the head box, said chamber further having an outlet in said head box extending substantially across the width of the head box, and vertical flow-turning vanes in said chamber curved through substantially 90° and forming flow-dividing passages extending horizontally between said intake and outlet for distributing the flow of stock through said outlet, said curved flow-dividing passages increasing in width in downstream direction.
